ADAM ZISKA, JR., OF MILWAUKEE, WISCONSIN, ASSIGNOR TO GEORGE W. ZISKA, OF CHICAGO, ILLINOIS.

LAMP SHADE AND PROCESS OF MAKING.

1,415,136.

Specification of Letters Patent. Patented May 9, 1922.

Application filed July 15, 1921. Serial No. 485,076.

To all whom it may concern:

Be it known that I, ADAM ZISKA, Jr., a citizen of the United States, residing at Milwaukee, county of Milwaukee, and State 5 of Wisconsin, have invented new and useful Improvements in Lamp Shades and Processes of Making, of which the following is a specification.

This invention relates to frames for lamp 10 shades and to the process of making such frames.

Objects of this invention are to provide a frame for a lamp shade in which the various members forming the frame are so organized 15 that they fit into each other; to provide a frame in which the various members may be readily soldered or otherwise secured with a minimum amount of material and with scarcely any exposure of the solder of other 20 material after the joint is made, thereby producing a neat and attractive frame free from bulges and unsightly or harmful protuberances; and to provide a frame for a lamp shade which is extremely rigid and 25 strong and which may be cheaply and rapidly manufactured.

Further objects are to provide a method for making a lamp shade frame which may be practiced to rapidly produce the frames; 30 which effects a saving in the material from which the frames are made; and which minimizes a number of operations necessary in the production of a finished lamp shade frame.

An embodiment of the invention is shown 35 in the accompanying drawings, in which—

Figure 1 is a side elevation, partly in section, of a completed lamp shade frame.

Figure 2 is a side view, partly in section, 40 of the upper ring and central hub or supporting piece.

Figure 3 is a fragmentary view of an indeterminate length of rod showing the manner in which successive members of the 45 frame may be cut from such rod without waste.

Figure 4 is a fragmentary sectional view on line 4—4 of Figure 2, on an enlarged scale.

In practicing this invention, the method 50 followed in the production of these lamp shades contemplates first, the production of a central hub member provided with a plurality of radially extending round holes. A 55 series of hexagonal or other polygonal rods

are then punched or cut into uniform lengths with a concave end formed upon one rod and a convex end to fit within the concave end of the succeeding rod, thereby avoiding waste. Thereafter, the convex ends of the 60 hexagonal rods are forced into the round holes in the hub member, thereby causing the corners to cut into the material or to force or swage such material outwardly, thereby binding the corners and rigidly securing the 65 rods in position. Thereafter, the radially extending rods may be bent at an angle to the plane of the hub or may be left extending outwardly in their initial state. A ring 70 is then formed of round stock and such ring may have its ends similarly formed, that is, concave and convex. This ring is fitted into the concave ends or socket portions of the radial rods and is soldered into place. Other rings, similarly formed and with spacing 75 members having concave ends, are then positioned and soldered and complete the frame.

Upon reference to Figure 1, it will be seen that the shade comprises a central hub member 1, which may have a central aperture 2 80 if desired, and which has a plurality of round radial extending holes 3. A plurality of hexagonal rods 4 are forced into these round openings and, as may be seen from reference to Figure 4, cause a distortion 85 of the metal forming the walls of these openings and allow the corners of the hexagonal rod to cut into such surrounding metal. It will be seen that this manner of securing the hexagonal or radial rods insures a firm union 90 which is secure against withdrawal of the rods or rotation of such rods. It will also be noted that the rounded inner end of these radial rods aids in entering such rods within the openings 3.

The structure shown in Figure 3 illustrates the manner in which successive rods 4 may be cut from an indeterminate length of stock. The stock is fed through a suitable machine and a cutting or punching 100 knife, having a rounded punch and a convex die, cuts the rod into suitable lengths and simultaneously forms the convex and concave ends without wasting of material. A similar manner of forming these convex 105 and concave ends may be employed for the rings 5 and 6 of the shade, such joints being shown at 7 and 8 respectively. After the radial rods are positioned within the hub they may be, if desired, given a slight an- 110

gular bend by simultaneously subjecting all the rods to suitably directed pressure, if the type of shade shown in Figure 1 is desired. It may happen, however, that a flat top frame is desired. In this case the central hub and radial rods are left in the position shown in Figure 2. The ring 5 is then placed in position and bears against the concave sockets or outer ends of the rods 4. 10 Thereafter, these joints between the ring 5 and the rod 4, together with the joints 7, are soldered. In a similar manner the ring 6 is formed, suitable spacing struts 9 being provided between the rings 5 and 6 and being formed with concave sockets at both ends. The joints between the struts 9 and the rings 5 and 6, as well as the joint 8, are now soldered.

It is to be noted, that by punching or cutting the rods in the peculiar manner illustrated, that the rings contact with such rods throughout their entire juxtaposed areas and therefore a minimum amount of solder is used and a maximum strength of joint results as distinguished from the joints which are usually made in frames of this type, such joints being weak and bulky and otherwise unsatisfactory.

By making lamp shade frames in the manner described, it is possible to rapidly assemble the parts and solder the joints with a minimum expenditure of time and with a minimum amount of handling. The resulting shade is extremely rigid and strong and is devoid of objectionable protuberances or bulging joints. It is also found that these frames may be made at a very much reduced cost as compared with the frames as formerly made.

40 I claim:

1. The method of making a lamp shade

frame, which method comprises forming a central hub with a plurality of round openings, inserting a plurality of radially extending rods of polygonal cross section into 45 said openings and forming concavities in the ends of said rods, forming a spring ring, and thereafter positioning said ring about the extremities of said rod by springing said ring and allowing it to snap into 50 the concavities of said rods.

2. A lamp shade frame comprising a hub portion having a plurality of substantially round openings, a plurality of radial extending polygonal rods forced into said 55 openings, and a ring joined to the outer ends of said radial rods.

3. A lamp shade frame comprising a substantially central member, a plurality of outwardly extending rods having sockets 60 formed in their outer ends, and a ring encircling said rods and socketed within the concave ends, said ring having a cross sectional contour corresponding to said concave ends.

4. A lamp shade frame comprising a plurality of inwardly extending members having concave outer ends, a ring surrounding said members and socketed within said concave ends and having a cross sectional contour 70 corresponding to the outline of the concave portions, and a frame work carried by said ring.

5. A lamp shade frame comprising a hub, a plurality of outwardly extending radial 75 members having concavities formed in their ends, a spring ring surrounding said rods and seated within the outer concavities thereof, whereby the members of said frame are inherently retained in their assembled 80 position.

ADAM ZISKA, JR.
